UNITED STATES PATENT OFFICE.

JOHN RYAN, OF CINCINNATI, OHIO.

BAND-SAW GUIDE.

SPECIFICATION forming part of Letters Patent No. 373,786, dated November 22, 1887.

Application filed July 11, 1887. Serial No. 244,041. (No model.)

To all whom it may concern:

Be it known that I, JOHN RYAN, a citizen of the United States, and a resident of Cincinnati, in the county of Hamilton and State of Ohio, 5 have invented certain new and useful Improvements in Band-Saw Guides, of which the following is a specification.

My invention relates to improvements in saw-guides used more especially as upper 10 guides in large or giant band-saw mills for controlling the saw in cutting logs; and my invention consists in providing an attaching base-plate, a two-part or open guide-supporting frame pivotally connected therewith at 15 one end, and an adjusting-screw connecting the other or free end of the guide-frame with the said base-plate, whereby said guide-frame is moved or turned on its axis, which is an eccentric one, and set in proper position, and the 20 band-saw, lying intermediate its two parts, simultaneously and properly set for operation upon the approaching log, all as hereinafter fully described.

Other features of my invention will be fully 25 set forth in the following description of the accompanying drawings, in which—

Figure 1 is a front elevation of my improved guide and a broken section of a band-saw shown in operative connection therewith; Fig. 30 2, a plan view of my invention, showing the guide mounted upon the outer end of one of the customary horizontal arms which project from the column or main frame of the band-saw mill, said arm being shown broken off 35 and the saw and one of the pivot-bolts of the guide in section; Fig. 3, a rear end elevation of the parts shown in Fig. 2, and Fig. 4 a central section showing the eccentric hinge or 40 pivotal connection between the attaching base-plate and the parts forming the guide-supporting frame.

A represents the customary guide-supporting arm (shown broken off, as above stated) which projects from the upright column or 45 main frame of a band-saw mill used for sawing logs into lumber.

a is an ordinary band-saw.

B represents a base-plate, preferably attached upon the end face of arm A by means 50 of one or more screw-bolts, b, passed through slots (shown in dotted lines b') therein, so as

to be longitudinally adjustable, to provide for saws of various widths.

C' represent lugs forming bearing boxes at one end of plate B, and D D' are rectangular longitudinal plates lying parallel with base-plate B, in front thereof, and forming the supporting-frame for the upright side guides, c' and d'. On the back of plate D', near its fore end, I provide an enlargement or lug, E, which is centrally bored to receive a pin or shaft, e. (Shown in dotted lines in Fig. 2 and in section in Fig. 4.) When the parts are fitted together, lug E lies intermediate the lugs C' on the base-plate, and is connected 60 with them by means of screw-bolts F F, which pass through smooth-bored holes in said lugs C' and rigidly engage threaded openings or sockets in shaft e, constructed in it out of center, as clearly shown in Figs. 2, 3, and 4. 70

f represents a set-screw entering the rear wall of lug E, with its point bearing upon shaft e to hold it firmly in the desired position.

g g represent screws, and g' g' nuts thereon, connecting the two plates D D' at the proper 75 distance apart to suit different thicknesses of saws used and make due allowance for wear of the upright side guides, said nuts being on the shanks of the screws intermediate said plates and jamming against the inner face of 80 plate D, as shown in Figs. 2 and 3. The upright guide-plates c' and d' are preferably made of brass, and are also arranged in pairs on the inner faces of the two supporting-plates D and D' near the fore ends thereof. Each 85 side guide is recessed on one of its faces to fit over said supporting-plates D D', and slots H are provided in both said supporting-plates, through which pass screws h, which adjustably secure the side guides in position to suit 90 the desired width of saw used. It is between these guides c' and d' that the saw runs, as shown in the first three figures of the drawings.

To readily track or set the saw so that it is guided direct and firmly held straight during 95 its cutting operation on a log, I provide, in connection with the eccentrically-disposed axle or bearing mechanism E e F and the side guides above described, a set-screw, I, at the other or rear end of the guide-supporting 100 plate D'.

J is a lock-nut on the shank of adjusting-

screw I, jamming against the outer face of plate D' when the screw is set at the desired position. A slot or recess, *i*, (shown in dotted lines, Fig. 2,) is made in the base-plate B, 5 through which the screw I passes into its threaded socket or hole in the arm A, to make provision for any required adjustment of said base-plate and the accompanying guide devices.

10 In the operation of my device, to track or set the saw to the right or left, according to the nature or position of the log, while it (said saw) is either running or at rest, the set-screws *f* and I are loosened and either of the screw-15 bolts F turned, so as to simultaneously turn the eccentric or shaft *e* the required distance. Then said set-screws are tightened or turned up to place, thereby firmly holding the guides in their set position throughout the entire cut 20 of the saw on the advancing log. The plain unobstructed face of plate D, occasioned by the countersinking of all the screws *g* and *h*, permits the claws or clamping-dogs which hold the log in place on its reciprocating carriage to pass freely and very closely thereto, and thereby reduces the thickness of the log or board remaining after the log has been sawed 25 to a minimum, thus insuring the sawing of each log entire into lumber uniformly and 30 without waste.

It is obvious that my guide, as above described, could constitute a lower one as well as an upper, except that a rear plate or friction-roller for the rear edge or back of the 35 saw should be provided in connection therewith to guide the saw in a proper manner to the lower band-wheel.

I claim—

1. A saw-guide composed of an open guide-frame consisting of plates D D', containing 40 and supporting any suitable side guides, one plate of said guide-frame being pivotally connected at one end with the guide-arm A or other suitable support on the main frame of a 45 band-saw mill by an eccentric hinge-joint, and provided at its opposite end with a set-screw, whereby the saw is properly set in line and

held so during the progress of the log advancing against its cutting-edge, substantially as herein set forth. 50

2. A saw-guide composed of an attaching base-plate, B, longitudinal supporting-plates or open frame D D', pivotally connected at one end by an eccentric joint, C C' E e F, with said base-plate, and provided at its other end 55 with a set-screw, I, or other suitable adjusting device, and upright side guides, *c c' d d'*, mounted on the inner faces of said plates D D', the whole being constructed, arranged, and attached upon the outer end of the usual guide-supporting arm of a band-saw mill, substantially in the manner and for the purpose specified. 60

3. In a saw-guide, the combination, with a base-plate, B, open guide-frame D D', upright side guides, *c c' d d'*, adjustably and detachably secured within said frame D D', the eccentric hinge-joint C C' E e F, and the set-screw I, of a set-screw, *f*, entering the rear wall of box or lug E on plate D', with its point bearing 70 against shaft *e*, to hold it firmly after setting, and thereby securely hold the saw against lateral or torsional strain while the log advances to it for cutting into lumber, substantially as herein set forth. 75

4. A saw-guide composed of the open frame D D', containing the side guides, *c c' d d'*, eccentric hinge-joint C C' E e F, and set-screw I, pivotally connecting said frame and its guides with the main frame of the mill, the 80 plate D' having a plain or unobstructed outer face, occasioned by the countersinking of the screws *g* and *h*, which secure the two parts of said frame D D' together, and also the side guides in place, whereby the saw is guided in 85 such a manner that logs may be sawed to a very narrow board or width without waste, substantially as herein set forth.

In testimony of which invention I have hereunto set my hand.

JOHN RYAN.

Witnesses:

JOHN E. JONES,
JOHN ADAM.
